Patented May 23, 1922.

UNITED STATES PATENT OFFICE.

DANIEL C. FISHER, OF BOSTON, MASSACHUSETTS.

LOCK VALVE.

1,416,807.

Specification of Letters Patent. Patented May 23, 1922.

Application filed March 3, 1921. Serial No. 449,486.

To all whom it may concern:

Be it known that I, DANIEL C. FISHER, a citizen of the United States, residing at Boston, in the county of Suffolk and State of Massachusetts, have invented new and useful Improvements in Lock Valves, of which the following is a specification.

This invention relates to a stop cock for controlling the flow of fluid through a conduit, such as the gasoline feed pipe of an explosive engine on a motor vehicle, the cock comprising a casing, having an internal valve seat and inlet and outlet passages at opposite sides of the seat, and a plug valve fitting said seat and adapted to be turned therein to open and close the cock.

The object of the invention is to provide a stop cock, the plug valve of which is adapted to be turned to open and close the cock, only by the barrel or cylinder and the key of a pin tumbler lock, such as the well known Yale lock. A lock of this type is recognized as affording a desirable degree of protection to property guarded by the lock.

The invention is embodied in the improvements hereinafter described and claimed.

Of the accompanying drawings forming a part of this specification,—

30 Figure 1 is a sectional view of a stop cock embodying the invention, the cock being closed.

Figure 2 is a view similar to Figure 1, showing the cock opened.

35 Figure 3 is a section on the plan of line 3—3 of Figure 2.

Figure 4 is a fragmentary side view, showing the interengaged portions of the lock barrel or cylinder and the plug valve.

40 Figure 5 is an end view, showing the inner or valve-engaging end of the lock barrel.

Figure 6 is a fragmentary sectional view, similar to a portion of Figure 1, showing a modification.

45 The same reference characters indicate the same parts in all of the figures.

In the drawings, 12 represents a cock casting or body having a tapered seat 13, in which the tapered plug valve 14 is fitted to turn. The casing has the usual inlet and outlet passages 15 and 16, and the plug valve has the usual transverse passage 17, which connects the passages 15 and 16 when the valve is open, the valve closing said passages when turned approximately ninety degrees from its open position.

The pin tumbler lock which is combined with the cock, includes the usual barrel adapted to be turned by a key, through an angle of ninety degrees. Said lock embodies nothing new with me, excepting as hereinafter pointed out.

The lock casing 19 is fixed to the cock body or casing 12, preferably by a pin 20, as shown by Figure 3. The lock barrel or cylinder 21 is in axial alinement with the plug valve 14, and is engaged with the latter preferably by means of a tongue 22, projecting from the inner end of the barrel, and a slot 23 formed in the outer end 70 of the plug valve, said tongue and slot presenting complementary interengaging faces which are formed to cause rotation of the plug valve by the barrel, and to permit independent endwise movement of the plug valve 75 by a spring 25, interposed between the barrel and the plug valve for a purpose herein-after stated.

As usual in locks of this type the barrel is normally locked in the case by spring pin 80 tumblers 26, and is unlocked by a key 27 having a stepped or irregular edge 28, adapted to displace said tumblers to permit a partial rotation of the barrel and the plug valve by the key. As in other locks of this 85 character, the case and tumblers are adapted to permit the insertion and removal of the key in and from the usual key slot 29 (Figure 5) only when the barrel is in the predetermined position shown by Figure 1, the 90 usual tumbler-guiding orifices 31 in the barrel being in alinement with the usual sockets 32 in the case, in which the spring-pressed barrel locking bolts 33 are movable, so that endwise movement of the key is enabled to displace the tumblers and the bolts. When the barrel is in the position shown by Figures 2 and 3, the tumblers are rigidly backed by the case 19, so that the key cannot be removed from the barrel. I so arrange the lock relatively to the cock body and its passages 15 and 16, that when the barrel is in said predetermined position the cock valve is closed, its passage 17 being out of alinement with the body passages 15 105 and 16. When the valve is open, as shown by Figures 2 and 3, the key cannot be removed from the barrel. The operator, therefore, knows that the valve is closed when the key is removed from the barrel, because 110 the key cannot be removed when the valve is not fully closed. The cock body 12 is

closed by an imperforate head 12^a at the smaller end of the valve seat, so that leakage from this end is impossible.

To compensate for wear of the valve seat 5 and the plug valve, I provide the spring 25 and the above-described complementary interengaging means on the barrel and the plug valve. Said spring is preferably helical, and bears at one end on the bottom of a 10 socket 36 in the plug valve, and at its opposite end on the barrel rib 22, as shown by Figures 1, 2 and 3. In the modification shown by Figure 6, the spring is of larger diameter, and one of its ends surrounds a 15 square shank or stud 39, projecting from the inner end of the barrel, the spring bearing on said inner end. The other end of the spring bears on the bottom of an annular socket 37 in the plug valve 14, said socket 20 surrounding a square inner socket 38, which receives the stud 39.

The spring-receiving recess is located between the valve passage 17 and the larger end of the valve, and the spring 25 is seated 25 at one end on the bottom of said recess, the opposite end being in position to be pressed inward by the lock barrel when the lock is inserted and secured in the socket of the cock casing. When the lock casing is in 30 place and is fastened by securing means, such as the pin 20, (Figure 3), the outer end of the spring is seated on the lock barrel and compressed thereby. The operation of 35 assembling the cock casing and lock therefore compresses the spring and causes it to hold the valve against its seat. The spring is located wholly within the periphery of the valve, so that I am enabled to employ a valve seat and valve of suitable length to 40 ensure a fluid-tight joint, without providing a space in the cock casing, outside the valve seat, for the reception of the spring. The length of the casing is, therefore, reduced to a minimum.

The lock case 19 is preferably fitted in a 45 socket formed in the outer end of the cock body, by an annular wall 40, integral with the cock body and adapted to be inserted in an orifice in a fixed support 41, which may be the instrument board or dash of a motor vehicle, the arrangement of the socket being such that when the lock case is inserted, the barrel is in alinement with the plug valve. The securing pin 20 is driven 50 through the wall 40 into the lock case as shown by Figure 3. Said wall is provided with means for securing it to the support 41, said means being preferably embodied in

an external screw thread 44 formed on the wall 40, and annular internally threaded 60 clamping plates or washers 42 and 43, formed to be screwed up against opposite sides of the support 41.

To prevent liability of the loosening of the clamping plate or washer 43 by the jar 65 to which the structure which includes the holder 41 is subjected, I provide the said washer with an annular lock-nut 45, having an internal thread engaging the external thread 44 on the annular wall 40, and an 70 external thread 46 engaging an internal thread 47 in an annular enlargement 48 on the washer 43. The pitch of the lock-nut thread 46 is opposite that of the wall thread 44, and the thread 46 is finer than the thread 75 44. The enlargement 48 and the annular lock-nut 45 are externally of hexagonal form, so that they may be simultaneously engaged by a wrench, and turned to force the washer 43 against the inner side of the 80 holder 14. After this has been done the wrench may be moved slightly sidewise and engaged only with the annular lock-nut 45. A slight turn of the lock-nut by the wrench now causes a binding action of the interengaged screw threads on each other, and locks 85 the inner washer against accidental turning.

I claim:

A stop-cock comprising a casing having at one end portion a tapered valve seat, and 90 at its opposite end portion a socket communicating with the larger end of the seat; a tapered plug valve fitting said seat, and provided between its ends with a transverse passage adapted to connect inlet and outlet 95 passages in the casing, and with a spring-receiving recess between said passage and the larger end of the valve; a pin tumbler lock, including a lock casing, and a valve-turning lock barrel adapted to turn without 100 endwise movement in the lock casing, said barrel and valve being provided with complementary interengaging faces causing the valve to turn with the barrel, and permitting independent endwise movements of the 105 valve; a spring located wholly within the periphery of the valve, and seated at one end on the barrel, and at its opposite end on the bottom of the said recess; and means securing the lock casing in said socket and 110 maintaining the barrel in position to compress the spring.

In testimony whereof I have affixed my signature.

DANIEL C. FISHER.
